CORE DRILLING DEVICE

Ralph A. Phillips, Hawthorne, and Mortimer L.
Clopton, Glendale, Calif.

Application May 6, 1940, Serial No. 333,548

6 Claims. (Cl. 255—72)

Our invention relates to a core drilling device for use in taking cores in the drilling of wells and has particular reference to a means for controlling the circulation of drilling fluid in and around the core carrier and to a means for registering the inclination of the well at the point at which the core is taken.

In the drilling of deep wells, such as oil wells, by means of rotary drilling rigs it is common practice to periodically take cores to provide samples of the formation through which the well is being drilled. These cores are cut by means of a coring bit adapted to cut away the formation in an annular fashion so as to leave a core extending upwardly from the bottom of the hole. Such coring bits are equipped with an inner core barrel or core carrier fitted with core catchers adapted to break off the core and convey the same to the ground surface at the time the bit is removed from the wall.

In early coring bit constructions it was found that the core was badly broken and shattered as a result of the inner core barrel being rotated with the bit and relative to the core and as a result of excessive pressures developed on top of the core by virtue of the circulating fluid being entrapped between the top of the core and the closed upper end of the core barrel. Attempts to prevent such breaking and shattering of the cores led to the development of core taking devices wherein the inner core barrel was rotatably supported upon the coring bit so that the core barrel could remain stationary relative to the core, and also to the provision in the upper end of the core barrel of a relief valve to permit fluid trapped above the core to be discharged as the inner barrel was gradually moved downwardly over the upstanding core.

It has been found that these expedients do not entirely solve the problem for the reason that during the time the bit is being initially lowered into the well bore preparatory to resuming a drilling operation, circulating fluid contained within the well bore flows into the core barrel through the core receiving aperture which is provided in the bottom of the coring bit. This drilling fluid is heavily laden with chips and fragments of stone dislodged by previous drilling operations so that when drilling is resumed these chips tend to wedge between the core and the core barrel to develop pressures tending to break the core. Furthermore, the chips get into the relief valve which is provided at the top of the core barrel and seriously impair the operation of that valve.

It is accordingly an object of our invention to provide a core drilling device which overcomes the above noted disadvantages.

It is an additional object of our invention to provide a core drilling device which includes a means for circulating clean drilling fluid through the core barrel before drilling is begun to wash out chips, fragments and the like which may be present therein.

10 It is a still further object of our invention to provide an apparatus of the character set forth in the preceding paragraph in which means is provided for preventing the flow of circulating fluid through the core barrel after the drilling is begun.

15 It is also an object of our invention to provide an apparatus of the character set forth in the preceding paragraphs which includes a means normally permitting the circulation of drilling fluid through the inner core barrel and which is actuatable from the ground surface to prevent such circulation through the inner core barrel.

20 It is a further object of our invention to provide an apparatus of the character set forth hereinbefore which includes a means responsive to flow of circulating fluid through the drill string for first permitting such fluid to be circulated through the inner core barrel and then to later prevent such circulation.

25 In connection with the taking of cores it is highly desirable to know the inclination of the well from the vertical at the point from which the core was taken in order that the geological data obtained may be properly correlated. This information is at present obtained by means of 30 separate inclination devices which may be either of the go-devil type introduced into the interior of the drill string and recovered by removal of the drill bit or of the wire line type which is lowered into the open hole and removed by means of a wire line. Both of these devices consume considerable time in their operation so that the drilling of the well is correspondingly delayed. Furthermore, there is always the attendant risk of losing these devices in the hole 35 so as to entail an expensive fishing operation in connection with their recovery.

40 It is therefore an additional object of our invention to provide a core drilling device of the character set forth hereinbefore which includes a means for ascertaining and registering the inclination of the well at the point where the core is taken to permit such inclination to be determined at the time the core is removed from the 45 well.

It is a still further object of our invention to provide a device of the character set forth in the preceding paragraph in which the device for registering the inclination is actuated in response to the starting of flow of circulation fluid through the drill string.

Other objects and advantages of our invention will be apparent from a study of the following specifications, read in connection with the accompanying drawings, wherein:

Fig. 1 is an elevation view of one form of core drilling device of our invention;

Fig. 2 is a fragmentary longitudinal section of the device illustrated in Fig. 1 showing the interior construction and the relative disposition of parts at the time the device is being lowered into the well;

Fig. 3 is a view similar to Fig. 2 but illustrating the relative disposition of the parts at the time the device has been lowered to the bottom of the well but before drilling has been started;

Fig. 4 is also a view similar to Fig. 2 but illustrating the relative disposition of parts after the drilling operation is begun;

Fig. 5 is an enlarged longitudinal section of the mechanism illustrated in the upper portions of Figs. 2 through 4 and showing the parts thereof in the positions they occupy prior to the beginning of a drilling operation; and

Fig. 6 is a view similar to Fig. 5 but illustrating the relative positions of the parts at the time the core is being taken.

Referring to the drawings, we have illustrated in Fig. 1 the preferred embodiment of our invention as including a coring bit head 1 which is attached by means of an adaptor 2 to a working barrel 3. The working barrel 3 may have secured to its upper end a pin half of a tool joint 4 to permit attachment to a drill collar or string of drill pipe by means of which the coring bit 1 may be rotated and urged downwardly to effect a drilling of the well. The engagement of the working barrel 3 with the tool joint 4 may be effected by means of a threaded connection 4a and similarly the engagement of the working barrel 3 with the adaptor 2 may be by means of a threaded connection 4b.

As is clearly shown in Fig. 1 the coring bit 1 includes cutting elements 5 and 6 adapted to engage the bottom of the hole and cut away the formation through which the well is being drilled. The bit 1 is provided with a central aperture 7 so that when the bit is rotated the cutters 5 and 6 will cut away the formation on an annular surface to define a central core which will be received within the aperture 7 as the bit gradually moves downward through the formation. As the core is thus moved upwardly through the aperture 7 it is received within an inner core barrel 8, which inner barrel is preferably rotatably supported upon the coring bit so that it may remain stationary with respect to the core to reduce the liability of breaking the core off as the drilling progresses.

This mounting of the inner core barrel 8 may be readily effected as by securing the bit head 1 to the adaptor 2 by means of screw threads 9 and by extending upwardly from the adaptor 2 a sleeve 10 which is interposed between the inner core barrel 8 and the working barrel 3 so as to define annular spaces 11 and 12 on opposite sides of the sleeve 10, the sleeve 10 being secured to the adaptor 2 as by means of screw threads 12a. The sleeve 10 is provided with a cap member 13 which may be attached to the upper end of the

sleeve 10 as by means of screw threads 14, the cap member 13 being bored and threaded as indicated at 15 to receive a supporting spindle 16.

The spindle 16 comprises a tubular member 5 which carries on its lower end a radially outwardly extending flange above which is placed a ball thrust bearing 18 in encircling relation with the spindle 16. The upper end of the inner core barrel 8 is similarly fitted with a cap member 19 which 15 may be attached thereto as by means of screw threads 20, the cap member 19 being provided with a central aperture adapted to loosely receive the spindle 16. Another ball thrust bearing 21 may be placed upon the spindle 16 above the cap member 19 and lock nuts 22 and 23 threadedly engaged with the spindle 16 20 may be employed for clamping the cap member 19 between the thrust bearings 18 and 21 and for clamping these three elements securely against the flange portion 17 of the spindle 16.

It will be seen that this structure operates to suspend the inner core barrel 8 from the upper end of the sleeve 10 and that such suspension permits rotation of the inner core barrel relative 25 to the sleeve and relative to the working barrel 3 to which the inner sleeve 10 is attached by the intermediary of the adaptor 2. The lower end of the inner core barrel 8 may be held in axial alignment with the core receiving bore 7 which 30 is provided in the bit 1 by providing an annular seat 24 within the adaptor 2 and disposed below the aforementioned screw threads 12a and by adjusting the length of the inner core barrel 8 in such manner as to cause the lower end thereof 35 to be rotatably received within the seat 24.

Our invention is directed to the provision of a means for controlling the circulation of drilling fluid through and around the inner core barrel 8. This control may be effected by means of a valve 40 mechanism which is enclosed within a housing 25 which is secured to the cap member 13 through the intermediary of a valve seat member 26. The valve seat member 26 is preferably threadedly secured as by means of screw threads 45 27 to an upwardly projecting end of the spindle 16 and is itself exteriorly threaded so as to provide a threaded engagement 28 with the housing 25.

The housing 25 is open at its top to provide 50 for the admission into the interior of the housing 25 of drilling fluid which is circulated through a wash opening 29 provided in the drill string attached to the tool joint 4. The wash opening in the tool joint 4 is preferably adapted to closely receive the upper end 30 of the housing 25 so as to prevent the passage of drilling fluid between the housing and the tool joint and to insure that all of the fluid circulated through the wash opening 29 will be passed into the interior 55 of the housing 25. The housing 25 preferably has an exterior diameter considerably smaller than the internal diameter of the working barrel 3 within which it is received so as to define an exterior annular space or circulating passage 31 between the housing 25 and the working barrel 3.

The housing 25 supports a timing mechanism 32 which will be described in detail hereinafter. The timing mechanism 32 supports a valve member 33 adapted to be urged downwardly by means of a spring 34 into engagement with a valve seat 35 formed in the upper edge surface of the valve seat member 26 and close off at this point the 70 passage formed by the housing 25. The valve 33 is supported from the timing mechanism 32

by means of a valve stem 36 which extends upwardly through the timing mechanism and carries on its upper end a latch member 37 adapted to be engaged by a pawl 38 which serves to hold the valve 33 in an open position as illustrated in Fig. 2 against the closing force of the spring 34. The pawl 38 is operatively connected as by means of a link 39 to a butterfly 40 extended across the interior of the housing 25 near its upper end. A plurality of fluid ports 41 communicating between the exterior and the interior of the housing 25 are provided just below the butterfly 40 which is mounted for pivotal movement between an upwardly inclined position, such as that illustrated by dotted lines in Fig. 2, and a depressed position, such as that illustrated in Fig. 3, the location of the ports 41 being so adjusted as to permit the exposing of these ports to the upper portion of the fluid passage within the housing 25 when the butterfly 40 is moved to the aforementioned depressed position.

The link 39 is so engaged with the butterfly 40 as to cause a withdrawal of the pawl 38 from the latch 37 when the butterfly is moved to this depressed position, thus permitting the spring 34 to close the valve 33. The aforementioned timing mechanism 32 operates to interpose a time lapse between the release of the pawl 38 and the actual closing of the valve 33.

We have illustrated in Fig. 2 the relative positions occupied by the various mechanisms described hereinbefore during the time the drill string is being inserted into the well bore, it being understood that a considerable proportion of the length of such previously drilled well bore is filled with drilling fluid which carries in suspension a considerable quantity of chips and fragments of the stone through which the bore is drilled. Consequently, downward movement of the bit 1 through the well bore and through the drilling fluid contained therein causes the drilling fluid to flow upwardly through the core receiving bore 7 in the manner indicated by arrows 42 in Fig. 2, this flow continuing upwardly past the valve seat 35 and outwardly through fluid ports 43 provided in the housing 25 just above the valve seat 35.

The flow of drilling fluid is joined, as it discharges from the ports 33, with a similar flow of fluid upwardly along the fluid space 12 defined by the working barrel 3 and the sleeve 10, the fluid gaining access to this space through conventional wash openings 44 provided in the adaptor 2. This fluid flow is indicated in Fig. 2 by arrows 45. The combined flow of the fluid through the fluid space 12 and through the core receiving aperture 7 continues, as indicated in Fig. 2 by arrows 46, to the upper end of the working barrel 3 where, by virtue of the ports 41, an upward pressure is exerted on the butterfly 40 to swing this butterfly into its upward position as indicated by dotted lines in Fig. 2 to permit the fluid to continue to flow upwardly through the wash opening 29 of the drill string.

Attention is called to the fact that by thus providing for upward fluid flow through the drill string, the resistance to the lowering of the drill string into the well which might be caused by the drilling fluid remaining within the bore is effectively relieved.

As soon as the bit has been lowered in the well bore to a position bringing the bit into engagement with the bottom of the bore, the flow of circulating fluid past the butterfly 40 stops

and the butterfly, by virtue of its own weight, is restored to an intermediate position such as that represented by the solid line position of the butterfly 40 in Fig. 2.

5 It will be appreciated that the interior of the inner core barrel 8 is, at this time, filled with drilling fluid containing a high percentage of rock fragments and chips and that before drilling is commenced, it is highly desirable that this fluid be washed out of the inner core barrel 8 and replaced by clean and fragment-free fluid supplied from the slush pumps located at the ground surface. The slush pumps are accordingly started and the downward flow of clean drilling fluid through the circulating opening 29 is begun as indicated by arrow 47 in Fig. 3. This flow imposes a pressure upon the upper surface of the butterfly 40 to force the butterfly into its depressed position, as illustrated in Fig. 3, and expose the ports 41 so as to permit the circulating fluid to pass from within the housing 25 into the fluid space 31 disposed exteriorly thereof, this flow being indicated in Fig. 3 by the arrow 48.

25 As pointed out hereinbefore, depression of the butterfly 40 releases the previously cocked valve 33 to permit it to begin its timed closing action. Prior to the actual closing of the valve 33, the downward flow of the fluid alongside the housing 25 will continue so as to force a part of that fluid to pass through the annular space 12 and outwardly through the wash opening 44 as indicated by arrow 49. The restriction which is afforded by the wash opening 44 also causes a part of the drilling fluid to pass through the ports 43 and enter the interior of the housing 25 below the timing mechanism 32 as indicated by arrow 50 in Fig. 3.

This flow of the drilling fluid passes downwardly through the bore provided in the supporting spindle 16 and into the inner core barrel 8 so as to displace the fluid previously contained in that inner core barrel as indicated by arrows 51. This cleaning of the inner core barrel continues until after the aforementioned lapse of time has transpired, at which time the valve 33 closes and seals off the passage into the inner core barrel which is afforded up to that time by the ports 43, thus causing all of the flow of circulating fluid to thereafter be directed through the annular space 12 and outwardly through the wash openings 44 in the conventional manner.

55 The positions occupied by the parts at the time the valve 33 is finally moved to its closed position is illustrated in Fig. 4. This is a position which is occupied by the parts during the time the bit 1 is being employed for the continued drilling of the well bore and for the production of a core sample to be taken by the bit. Reference to Fig. 4 will show that as the bit progresses downwardly through the formation being drilled, the core receiving aperture 7, by virtue of the omission of cutting elements at that point, operates to leave an upstanding core 52 which, as the drilling progresses, moves upwardly relative to the inner core barrel 8. This movement of the core 52 relative to the core barrel 8 must of a necessity displace from the inner core barrel the drilling fluid which is contained in the upper portion thereof. This fluid may be readily discharged by providing near the upper end of the inner core barrel 8 a plurality of ports 53 which communicate between the interior of the core barrel 8 and the aforementioned annular space 11 so as to cause the fluid which is dis-

placed by the core 52 to be passed, as indicated by arrows 54 in Fig. 4, into the annular space 11.

The fluid may be discharged from the annular space 11 by means of auxiliary ports 55 which are formed in the body of the adaptor 2 and extended between the lower end of the annular space 11 and the aforementioned wash openings 44. The auxiliary ports 55 are preferably inclined in such manner as to intersect the wash openings 44 at a forwardly directed angle so that the high velocity flow of drilling fluid through the wash openings 44 operates to create a suction in the auxiliary ports 55 by an injector action. This tends to further facilitate the removal of the drilling fluid which is contained between the top of the core 52 and the upper end of the inner core barrel 8 so as to insure against possibility of building up within the inner core barrel 8 any pressure which would inhibit the drilling of the well.

When drilling has progressed sufficiently to provide a core 52 of the desired length, the core is broken from the parent formation to which it is attached by conventional practice through the use of a conventional core catcher 56 which is secured to the bit head 1.

It will be observed from the foregoing that the washing out of the inner core barrel 8 is permitted by virtue of the fact that the valve 33 is initially placed in its open position and latched in that position by the engagement of the pawl 38 with the latch 37, and that the sealing off of the fluid communication between the channel through which the drilling fluid is circulated and the interior of the inner core barrel 8 is effected by the closing of the valve 33.

Attention is also called to the fact that the closing of this valve is automatically initiated by the beginning of the circulation of the drilling fluid which is employed to wash the interior of the inner core barrel. This operation is permitted by the use of the timing mechanism 32, the construction of which is illustrated in detail in Fig. 5.

The timing mechanism 32 comprises a cylinder 57 within which is reciprocably mounted a piston 58, the piston 58 being secured to the aforementioned valve stem 36 and adapted to make a sealing fit with the walls of the cylinder 57 as by means of piston rings or suitable packing material 59. The cylinder 57 is fitted with upper and lower cylinder heads 60 and 61, fluid leakage around the valve stem 36 being prevented by means of suitable packing glands 62 and 63. The entire space within the cylinder 57 not occupied by the piston 58 is filled with a suitable fluid, dashpot oil being found eminently satisfactory for this purpose.

The piston 58 is provided with one or more bores 64 which extend between the upper and lower surfaces of the piston 58 to permit passage of fluid therethrough as the piston is moved in the cylinder. Each of these bores 64 is provided with a check valve 65 which operates to permit only downward flow of fluid through the bores 64. This permits the piston to be readily moved to the upper end of the cylinder 57 at the time the valve spring 34 is compressed to latch the valve in its open position. One or more timing openings 66 are also extended longitudinally through the piston 58 so as to provide for upward flow of fluid as the piston 58 moves downwardly in the cylinder 57.

It will be readily appreciated that the combined cross sectional area of the openings 66 may be so adjusted as to provide for any desired rate of

travel of the piston 58 in response to the downward force exerted thereon by the spring 34 after the pawl 38 has been released from the latch 37. It will thus be seen that when the pawl 38 is released as by the starting of the slush pumps at the ground surface, the valve 33 immediately begins a slow downward movement in response to urging of the spring 34 and that the rate of this downward movement is so controlled as to 10 permit sufficient length of time to elapse between the starting of the slush pumps and the closing of the valve 33 to provide for the complete cleaning of the inner core barrel 8.

Reference has been made hereinbefore to the 15 desirability of obtaining a registration of the inclination of the well bore to the vertical at the point the core is taken. Our invention comprehends the use of the valve 33 and the timing mechanism 32 associated therewith as a means 20 for obtaining such a registration. As shown in Fig. 5 the valve seat member 26 is preferably provided at a point below the valve seat 35 with a spider 67 which is used to support a pendulum 68. The pendulum 68 preferably comprises an 25 upwardly extending rod 69, the upper end of which is sharpened to a point as indicated at 70 and the lower end of which carries a weight or plumb-bob 71. The rod 69 is supported by the spider 67 by means of a universal joint 72 permitting free pivotal movement of the rod 69 about the joint 72 in any vertical plane so that the rod 69 will remain in a truly vertical position irrespective of the inclination of the axis of the housing 25 within which it is supported.

35 The lower face of the valve 33 is preferably recessed as indicated in Fig. 5 to frictionally retain an indicator disk 73 and the length of the rod 69 is so adjusted that the point 70 will provide a pin prick or depression in the card 73 40 when the valve 33 is moved to its completely closed position. This relationship is illustrated herein in Fig. 6. The indicator card 73 may, if desired, be provided with a series of concentric circular gradations each representative of a 45 predetermined angular amount of inclination of the well bore so that when the core cut by the coring bit is removed from the well, an inspection of the card 73 to reveal the position of the pin prick therein relative to these concentric 50 gradations will provide a registration of the angular inclination of the well bore to the vertical at the point at which the taking of the core was begun. Excessive pressures on the universal joint 72 and on the spider 67 may be prevented 55 by recessing the valve 33 behind the card 73 and by filling this recess with a resilient or semi-plastic material.

60 Attention is called to the fact that the registering of the angle of inclination of the well bore to the vertical is initiated after the device is lowered into the well bore by the starting of the slush pumps at the ground surface. It will be 65 readily appreciated that the position occupied by the pendulum relative to the housing 25 will be seriously disturbed by the flow of circulating fluid past the weight 71 so that it is advisable to stop the slush pumps when they have been operated a sufficient length of time to completely wash the inner core barrel 8 but before a sufficient time has elapsed to permit the timing mechanism 32 to cause the card 73 to be moved into engagement with the plumb-bob point 70, thus providing a period of time during which the plumb-bob is permitted to come to rest and assume a truly vertical position.

After a sufficient length of core has been cut and the core has been broken from the parent formation in the manner hereinbefore described, the drill string is removed from the well bore to bring the device of our invention and the core carried thereby to the ground surface. Upon arrival at the ground surface the bit head may be separated from the adaptor 2 at the threaded connection 9 to permit the withdrawal of the core 52 from the core barrel 8 or, if preferred, the adaptor 2 may be unscrewed from the working barrel 3 at the threaded connection 4b so as to permit the withdrawal from the working barrel 3 of the sleeve 10 and the inner core barrel 8 carried thereby. The caps 13 and 19 may then be removed from the sleeve 10 and the core barrel 8, respectively, to permit extraction of the core 52 through the upper end of the core barrel 8.

Access may then be had to the indicator card 73 by separating the housing 25 from the valve seat member 26 at the threaded connection 28.

From the foregoing it will be observed that we have provided a core drilling device including a core receiving barrel which is so constructed as to permit the replacement of chip laden drilling fluid in the barrel with clean drilling fluid prior to the time the drill is operated to take a core.

It will be further observed that the device of our invention permits the washing of the core barrel to be terminated after a predetermined length of time to thereafter prevent the drilling fluid from being forced into the core barrel.

Attention is called to the fact that the device of our invention includes a means which is responsive to an operation performed at the ground surface (in the modification shown herein in the operation of starting the slush pumps) for changing the path of flow of the drilling fluid from one extending through the core receiving barrel to another exteriorly thereof and that such change in path of flow occurs a predetermined time after the performance of the operation at the ground surface.

While we have shown and described a butterfly coacting with a hydraulically timed valve for performing this operation, it will be understood that this invention is not limited to the use of a hydraulic device for effecting the desired timing function, nor is this invention limited to the employment of a butterfly for placing the timing mechanism in operation, it being understood that other forms of timing devices and other types of flow responsive means may be used with equal satisfaction for starting and performing the timing operation.

While we have shown and described the preferred embodiment of our invention, we do not desire to be limited to any of the details of construction shown or described herein, except as defined in the appended claims.

We claim:

1. In a core drilling device including a tubular working barrel having means for attachment to a string of drill pipe and carrying a coring bit, the combination of: a tubular core receiving barrel so disposed within said working barrel as to define an annular fluid passage between said barrels, said core barrel having an opening near its upper end establishing a fluid interconnection between the interior of said core barrel and said passage, whereby fluid supplied through said drill string will be simultaneously passed through said passage and said core barrel; valve means for closing said opening to prevent passage of

fluid through the interior of said core barrel; spring means normally urging said valve toward a closing position; releasable restraining means for holding said valve in an open position; means responsive to flow of fluid in said drill string for releasing said restraining means; and means operable independently of flow of fluid in said drill string for delaying the actual closing of said valve for a predetermined time after release of said restraining means.

2. In a core drilling device including a tubular working barrel having means for attachment to a string of drill pipe and carrying a coring bit, the combination of: a tubular core receiving barrel carried by said working barrel and having an opening in its upper end through which drilling fluid may be circulated; valve means actuatable to close said opening; means controllable from the ground surface to actuate said valve means; means on said core barrel for determining the angle of inclination of said barrel to the vertical; and means responsive to actuation of said valve means for producing a registration of said angle.

3. In a core drilling device including a tubular working barrel having means for attachment to a string of drill pipe and carrying a coring bit, the combination of: a tubular core receiving barrel carried by said working barrel and having an opening in its upper end through which drilling fluid may be circulated; valve means actuatable to close said opening; means responsive to flow of fluid in said drill string for actuating said valve means; means on said core barrel for determining the angle of inclination of said barrel to the vertical; and means responsive to actuation of said valve means for producing a registration of said angle.

4. In a core drilling device including a tubular working barrel having means for attachment to a string of drill pipe and carrying a coring bit, the combination of: a tubular core receiving barrel carried by said working barrel and having an opening in its upper end through which drilling fluid may be circulated; valve means mounted for movement to a position closing said opening; means responsive to flow of fluid in said drill string for moving said valve to said closed position; inclinometer means on said core barrel for determining the angle of inclination of said barrel to the vertical; and registering means carried by said valve in a position to engage said inclinometer means upon movement of said valve to said closed position to thereby register the angle determined thereby.

5. In a core drilling device including a tubular working barrel having means for attachment to a string of drill pipe and carrying a coring bit, the combination of: a tubular core receiving barrel carried by said working barrel and having an opening in its upper end through which drilling fluid may be circulated; valve means mounted for movement to a position closing said opening; means controllable from the ground surface to move said valve means to said closed position; a record chart carried by said valve means; a pendulum carried by said core barrel for determining the angle of inclination of said barrel from the vertical, said pendulum including a pointer for indicating said angle; and means mounting said pendulum in such position as to engage said pointer with said chart when said valve is moved to said closed position to thereby record the angle determined by said pendulum.

6. In a core drilling device including a tubu-

lar working barrel having means for attachment to a string of drill pipe and carrying a coring bit, the combination of: a tubular core receiving barrel so disposed within said working barrel as to define an annular fluid passage between said barrels, said core barrel having an opening near its upper end establishing a fluid interconnection between the interior of said core barrel and said passage, whereby fluid supplied through said drill string will be simultaneously passed through said passage and said core barrel; valve seat means surrounding said opening; valve means including a valve stem guided for axial sliding movement of said valve into engagement

with said valve seat; spring means normally urging said valve toward said seat; latching means engaged with said stem for holding said valve away from said seat; means responsive to flow of fluid in said drill string for releasing said latch means; a piston carried by said stem; a closed fluid filled cylinder surrounding said piston; and timing passages communicating between opposite end portions of said cylinder for permitting slow movement of said valve toward said seat when said latch is released.

RALPH A. PHILLIPS,
MORTIMER L. CLOPTON.
